UNITED STATES PATENT OFFICE

2,489,941

RECORD CHANGER

Milton A. Walker, San Jose, Calif.

Application May 3, 1944, Serial No. 533,819

7 Claims. (Cl. 274—10)

1

The present invention relates to improvements in record changers, and has particular reference to phonographs designed to allow a plurality of records to be played in automatic succession and without the intervention of any human agency.

While phonographs of this type are well known and in common use at the present time, it is proposed to introduce a new method of operation which has not been contemplated heretofore as far as I am aware.

More particularly, it is proposed to use a process in which air under pressure is introduced between a record and its support, such as a turn-table or another record lying underneath, to facilitate sliding movement of the record on its support.

It is further proposed to use the force of gravity for moving the record, this force being created through a slight inclining of the record supporting table or tables.

It should be particularly understood that the interposing of the air film makes it practical to use the force of gravity for sliding the record from one table to another, the air film serving the purpose, not only of breaking contact between two adjacent records so as to prevent injury to the grooves of the records, but also that of furnishing an anti-friction bearing for the record to be moved, whereby the latter will respond to a very slight inclination.

And finally, it is proposed to provide certain other improvements in details of construction, as well as in the general plan to render my basic idea available for practical purposes.

Further objects and advantages of my invention will appear as the specification proceeds, and the novel features of my record changer will be fully defined in the claims hereto attached.

The preferred form of my invention is illustrated in the accompanying drawings forming part of this application, in which:

Figure 1 shows a vertical longitudinal section through the main operating mechanism of my record changer;

Figure 2, a top plan view of the record changer;

Figure 3, a horizontal section taken along line 3—3 of Figure 1;

Figure 4, a detail view of a microphone pick-up arm and its operating mechanism;

Figure 5, a vertical section through the arm-operating mechanism;

Figure 6, a horizontal section taken along line 6—6 of Figure 1; and

Figure 7, a wiring diagram explaining the sequence of operations.

2

While I have shown only the preferred form of my invention, I wish to have it understood that various changes or modifications may be made within the scope of the claims hereto attached, without departing from the spirit of the invention.

5 Referring to the drawing in detail, my apparatus may be accommodated in any suitable cabinet 1, which may be rectangular in form and may comprise a bottom 2, end walls 3 and side walls 4. A top 5 for the cabinet is formed with a large opening 6 adapted to accommodate and give access to the records and the main working mechanism.

10 A base board 7 of any suitable width is hinged to one of the end walls, as at 8 and extends substantially through the length of the cabinet in spaced relation to the bottom of the same, and its free end is supported on a cam 9 secured upon a large wheel 10 adapted to be driven by the motor 11.

15 Rotation of the cam through one-half of a revolution causes the base board to dip or tilt, while a further rotation through one-half a revolution causes the base board to return to horizontal position.

20 The base board carries a U-shaped wall 12 which serves as a guide for guiding the records from one table to another, as will be more fully described hereinafter. The upper portion of the guide may be provided with a suitable felt lining as indicated at 13.

25 The base board further carries, intermediate its length, a post 14, which pivotally supports a beam 15 having two forked ends 16 and 17 on which the table assemblies rest.

30 My apparatus comprises two table assemblies, one for the rotary table 20 adapted to carry a stack of records 21 to be played, and one for the non-rotating table 22 adapted to receive the records which have been played.

35 The two table assemblies are supported on the ends of the beam 15 by means of cupped discs 23—24, and the non-rotating table assembly is weighted, as at 25, to be always heavier than the rotating table assembly, even if all the records are stacked on the latter.

40 The supporting means for the non-rotating table assembly comprises a tube 26 rising from the base board and secured thereto by means of a holding plate 27 fixed to the underside of the base board by means of rivets 28, and a tube 29 depending from the table and telescoped on the tube 26.

45 An air tube 30 extends centrally through the tubes 26 and 29, and connects, below the base

board, with a main air tube 31. The upper end of the air tube 30, which is fixed in its position, is on a level with the top of the table when the latter is in its uppermost position, or on a level with the topmost record placed on the table, so as to serve as a centering pin for the records. The tube terminates in a small orifice or jet, as at 32, for allowing air to escape therethrough.

The table 22 is lowered stepwise, by the thickness of one record, whenever a record is received on the table. The apparatus bringing about this effect comprises a stepped block 33 having steps 34 corresponding in depth to the thickness of a record, a foot 35 depending from the tube 29 and adapted to rest on one of the steps, and operating means for the block, whereby the latter is pulled to the left by the width of one step each time a record is received on the table.

The operating means for the block comprise an electro-magnet 36 pulling against a spring 37. The core 37' of the electro-magnet, which has a bend to limit its inward motion, terminates in an arm 38 running alongside of the block, and the arm and the block are provided with a suitable pawl and ratchet arrangement 39-40, whereby the block is pulled to the left by the width of one step each time the electro-magnet is energized. A spring 40' tends to push the core outward for a new bite.

The foot 35 bearing against the vertical wall of each step serves as a stop for holding the block in position after each move. The block is formed with a lengthwise slot 41 by means of which it is made to straddle the tube 26, and movement toward the right beyond the extreme position shown in Figure 1 is prevented by the end wall of the slot.

The rotary or turntable assembly includes a tube 45 rising from the base board 7, a motor assembly 46 mounted underneath the turntable and comprising a non-rotary part 47 and a rotary part 48, a tube 49 projecting downwardly from the non-rotary part of the motor and telescoped over the tube 45, a third tube 50 rising from the concave disc 24 and telescoped over tube 49, spring means 51 for urging the concave disc and non-rotary part of the motor apart, and releasable means 52' for locking tube 50 to tube 49 and for holding the disc 24 and the non-rotary part of the motor in fixed relation.

The contacting faces of the tubes 45, 49 and 50 are made non-circular or polygonal, so as to prevent relative rotation and to hold the part 47 of the motor against rotation.

The motor 46 may be made of any suitable type, and is here shown as comprising, in its non-rotating part, a laminated core disc 52 and a series of coils 53 supported on arms 54 projecting from the upper end of the tube 49; and, in its rotary part 48, a laminated ring rotor, secured upon the lower face of the turntable 20. The latter has a depending annular flange 55 resting on the upper end of the tube 49, which is suitably widened to furnish a bearing surface.

The means 52' for releasably locking the tube 50 to tube 49 comprise a rack 56 on tube 49, a pinion 57 mounted on tube 50 to mesh with the rack, and a solenoid 58 having a plunger 59 normally locking the pinion against rotation. When the solenoid is energized, the plunger is withdrawn and relative adjustment may be made between the two tubes. The switch 95' for the solenoid is arranged for convenient manual operation.

Thus, normally, the concave disc 24, the tubes

49 and 50, and the non-rotating part of the motor form a rigid assembly, movable as a unit, but the length of this unit may be adjusted, depending upon the number of records used, to bring the top record into the proper position with respect to the remainder of the apparatus when the beam 15 is in the starting position, shown in Figure 1.

When in playing position, the top record 10 should be located immediately above the top plane of the table 22, or if the latter carries records, above the top plane of the uppermost record carried thereby.

An air tube 60 extends centrally through the tube 45, the table and the record assembly thereon, and is connected, through a flexible hose 61, with the main air tube 31. It is normally urged upward to come flush with the top face of the uppermost record, by means of a spring 62 bearing at one end upon a cage 63 secured to the bottom face of the base board 7, and at its upper end upon a disc 64 secured upon the air tube.

When the topmost record is to be removed, by the sliding motion developed in the invention, 20 the air tube has to be retracted by the thickness of the record, and this is accomplished by means of a solenoid 65 acting on a coupling 66 of magnetizable material, this coupling being connected to the hose 61 by means of a nipple 67 of non-magnetizable material.

The air tube 60 is formed with a reduced orifice or nozzle 68 at its upper end.

A third air tube 70 rises from the main tube 31 along the edge of the table 20 nearest the cabinet wall to which the base board 7 is pivoted. This tube is provided with a lateral nozzle 71 directed at the plane between the two uppermost records and is intended to blow a film of air underneath the topmost record.

40 The film of air will relieve binding contact between the uppermost record and the next one and will start sliding movement of the record toward the second table as soon as the baseboard is tilted. The record thus practically floats on air, all friction is eliminated and the record will start moving in response to a very slight gravitational force.

The space between the two tables is occupied by a cover plate 72, the top of which is on a level 50 with the top of table 22 (when empty) and the top of the second record on table 20, so that the top faces of the table 22, the cover plate 72 and the second record form a common plane on which the top record may slide, supported by the air cushion, from one table to the other, when the common plane is tilted.

The cover plate 72 has two air tubes 73 projecting therethrough on opposite sides of the centerline of the two tables. The latter tubes 60 connect with the main tube 31 and extend to the top of the cover plate, where they discharge through nozzle 74.

The main air tube is controlled by an electrically operated valve 75. This valve is operated 65 in timed relation to the tilting of the base board, so that when the board is tilted, the air blows between the two uppermost records from tube 70 to create an air film or an air float which allows the record to start moving, the air tube 60 having been withdrawn sufficiently to clear the record.

As the record slides down the inclined plane formed by the second record, the cover plate 72 and the second table, the air tubes 60, 73 and 30 75 successively supply the necessary air to maintain

the air film, and the record thus easily gravitates upon the table 22, being guided by the U-shaped guide 12 and its lining which stop the record when it becomes centered over the table 22.

The microphone pickup arm 80 may be mounted in a post 81 rising from a bracket 82, which latter may be secured upon the U-shaped guide 12, at one side of the turn table. The post is revolvable about a pin 83 (Figure 4), and the arm is pivoted in the post with freedom of swinging movement in a vertical plane.

The post 81 has a brace 84 projecting over the arm 80, and the brace carries an electro-magnet 85 disposed above an intermediate section of the arm 80. The electro-magnet carries a core 86 of magnetizable material and the arm 80 has an insert 87 of the same material right underneath the core. The latter also carries a pin 88 projecting through the insert and formed with a head underneath the same.

The core 86 has a disc 87' secured thereto, and a bellows 88' connects the disc 87' and the lower end of the electro-magnet so as to form a contractible chamber about the core 86, this chamber connecting into the chamber 89 above the core, which latter is closed at the upper end by the top plate of the electro-magnet. The latter plate has a large opening 90 with a ball valve 91, and a restricted orifice 92.

Due to this construction, when the magnet is energized, the insert 87 in arm 80 is attracted immediately to the core 86, and the latter, with the bottom plate 87' of the bellows, is pulled upward, the excess air from the bellows and the front chamber freely escaping through the check valve 91.

As the magnet is de-energized, the insert of arm 80 naturally drops away from the core, but the amount of this drop is limited by the head of the pin 88. The core also tends to drop immediately, but its downward progress is retarded by suction, since the valve 91 automatically closes and a certain amount of time is consumed in supplying the air needed for the expansion of the bellows through the limited aperture 92. Thus the arm 80 is lifted quickly, but is let down slowly.

Horizontally, the arm 80 travels from left to right (Figure 2) while the record is being played, is then lifted by the electro-magnet, swings back to an initial position (from right to left) by gravity when the entire apparatus is tilted for transferring a record, and is let down to the new record after the top record has been transferred.

The post 81 has an arm 93 projecting rearwardly therefrom to close a switch 94 for energizing the electro-magnet when the arm 80 has reached the end of its inward movement.

To prepare for use, the operator first presses down on the turn table 20 to bring the concave disc 24 to its lowermost position, as indicated in Figure 1. This will bring the table 22 to its uppermost position, on a level with the top plate 72, and will cause the spring 37 to pull the stepped block 33 to the right so that foot 35 comes to rest on the highest step, suitable means being provided for disengaging pawl 39 during this operation.

The operator then places the desired number of records on the turn table 20, pushes the switch 95' (see wiring diagram) energizing magnet 58, which unlocks the tube 49 from the tube 50, and then allows the spring 51 to raise the turn table until the uppermost record is in the correct position, that is, immediately above the plane of the 75

top plate 72 and the table 22. The switch is then released.

The sequence of operations may be best explained by means of the wiring diagram of Figure 7, in which a main line switch is shown at 95, differential relay switches 96, 97, 98 and 99, and special switch members 100, 101, and 102, and in which the wires have been lettered as shown.

Assuming that the phonograph is playing, with both switches 95 and 96 closed, and the needle reaches the end of the record so as to close switch 94, the following operations take place:

1. Current flows through wire a, 93, 94, h, wire p, opening relay of switch 96 and back to wire b; switch 96 opens; motor 46 stops.

2. Current flows through wire a, arm 93, 94, closing relay of 97, and wire b; switch 97 closes, and current flows from wire a, through relay 97, magnet 85 and back to wire b. Magnet 85 lifts tone arm.

3. Current flows through wire a, arm 93, 94, wire d, magnet 65, and wire e to b; magnet 65 pulls down air tube 60.

4. Current flows through wire a, arm 93, 94, wire d, wire f, closing relay of 99; wire g, and back through e to b; closes switch 99; current flows from a through 99, magnet 75, and wires g, e, back to b; magnet 75 opens air valve.

5. Current flows from wire a, through 93, 94, wire h, closing relay of 98, and to negative lead B; closes switch 98; current flows from positive lead A through switch 98, motor 11, to negative lead B. Motor 11 turns cam 9.

35 The record slides over, becomes centered and the tone arm swings from right to left, opening switch 94, which deenergizes solenoid magnet 65 allowing air tube 60 to rise, to act as centering pin for a new top record.

46 6. As the cam reaches lowermost position, contacts close at 101, current flows from a through i, 101, k, opening relay of 99, through g, e to b, opening 99 and stopping flow of air.

45 7. Cam lifts platform 7 on completing one rotation and member 100 closes switch 102; temporarily current flows from wire l through 102, m, magnet 36 and back to B; magnet 36 pulls back the stepped block 34.

46 8. At the same time current flows from l through 102, n, and opening relay of 98, opening the latter and stopping motor 11.

47 9. At the same time current flows from l through 102, wire o, and closing relay of 96 to b, closing switch 96, and starting motor 46.

55 10. At the same time current flows from l through 102, wire q, opening relay for switch 97, and back to b; switch 97 opens; tone arm drops.

I claim:

1. In a record changer of the character described, two tables adapted to have records stacked thereon, a tiltable base board having a post thereon, a beam pivoted in the post and having the tables supported on the ends thereof, means operable for positioning the tables in fixed relation to the baseboard and at related elevations to allow one record to slide from one table to the other and means for tilting the base board to effect such sliding motion.

2. In a record changer of the character described, two tables adapted to have records stacked thereon, a tiltable base having a post thereon, a beam pivoted in the post and having the tables supported on the ends thereof, means operable for positioning the tables in fixed relation to the baseboard and at related elevations to allow one record to slide from one table to the other and means for tilting the base

tions to allow one record to slide from one table to the other, means for tilting the base to effect such sliding motion, and means operable for vertically shifting the tables after a record has been transferred to again establish related elevations.

3. In a record changer of the character described, two tables adapted to have records stacked thereon, a tiltable base board having a post thereon, a beam pivoted in the post and having the tables supported on the ends thereof, means operable for positioning the tables in fixed relation to the baseboard and at related elevations to allow one record to slide from one table to the other, and means for blowing air underneath the record to be moved to relieve friction for facilitating the sliding movement when the baseboard is tilted.

4. In a record changer of the character described, two tables adapted to have records stacked thereon, a platform between the tables, means for positioning the tables with respect to the platform to provide a common plane for a record to slide from one stack to the other, and means for blowing air underneath the record at said common plane to relieve friction for facilitating the sliding movement of the record when the plane is tilted.

5. In a record changer of the character described, two tables adapted to have records stacked thereon, a platform between the tables, means for positioning the tables with respect to the platform to provide a common plane for a record to slide from one stack to the other, means for tilting the common plane to set up a gravitational force for urging the record to move, and means for blowing air underneath the record to eliminate frictional resistance to the transfer.

6. In a record changer of the character described, two tables adapted to have records stacked thereon, a platform between the tables, means for positioning the tables with respect to the platform to provide a common plane for a record to slide from one stack to the other, means for tilting the common plane to set up a gravitational force for urging the record to move, and

means for blowing air underneath the record to eliminate frictional resistance to the transfer, the said means comprising means for injecting air underneath the record progressively at the upper end of the record and at spaced points during its travel.

7. In a record changer of the character described, two tables adapted to have records stacked thereon, a platform between the tables, means for positioning the tables with respect to the platform to provide a common plane for a record to slide from one stack to the other, means for tilting the common plane to set up a gravitational force for urging the record to move, and means for blowing air underneath the record to eliminate frictional resistance to the transfer, the said means comprising means for injecting air underneath the record progressively at the upper end of the record and at spaced points during its travel, and lateral supporting means being provided for guiding the record from one table to the other.
